UNITED STATES PATENT OFFICE.

HARRY II. CABOT, OF BRISTOL, ASSIGNOR TO THE KENT & STANLEY COMPANY, OF PROVIDENCE, RHODE ISLAND.

DESIGN FOR A SPOON.

SPECIFICATION forming part of Design No. 28,195, dated April 17, 1894.

Application filed March 8, 1894. Serial No. 502,917. Term of patent 14 years.

To all whom it may concern:

Be it known that I, HARRY II. CABOT, of Bristol, in the county of Bristol and State of Rhode Island, have invented and produced a new and original Design for Spoons, of which the following is a specification, reference being had to the accompanying drawing, forming part thereof.

The drawing represents a view of a spoon illustrating my new design.

The general features of my new design for spoons consist in the general design included within the outline of the bowl illustrating a pitcher-shaped cup having a contracted base and pedestal, an enlarged bulbous body surmounted by a contracted neck having a pitcher-shaped or lipped top, and a scrolled handle extending from above the top to the upper side portion of the body, together with surface ornamentation to accentuate the different portions of the design.

In the drawing 5 indicates the bowl of a spoon within the outline of which the new design is applied, the base of the design is located near the tip of the same and consists of the curving outline 6, above this the outline at each side contracts to 7—7, then expands to 8—8 where it abruptly spreads outward to 9—9, thence curving outward and inward to 10—10 and again boldly outward and upward

to 11—11, the greatest diameter of the design,—the outline now curves generally inward and then upward to 12—12, then outward and upward nearly vertically, again inward to 13—13, then upward and generally outward in broken curves to the point 14 at one side and to the point 15 at the other, these points being connected by a wave-like line 16, from the point 15 the outlines of the handle form scrolls 17 and 18 connected by 40 the shaft 19 their general direction being downward to meet the curved ornament 20.

The surface ornamentation consists of beadings at the base below 7—7, the foliations 23, the oval shaded panel 25 merging into the 45 portion below the same, the ornament 24, the foliated collar 26, and the ornamented bands connecting the outlines above this collar, together with surface shade lines to accentuate the various portions of the design. 50

What I claim is—

The design for spoons as herein shown and described.

In witness whereof I have hereunto set my hand.

HARRY II. CABOT.
